ABSTRACT: For pressure bonding the joint between two angularly related frame members, a pair of clamps, disposed, one against each side of said frame members and spanning the joint involved, said clamps being interconnected by bolts through the frame members to either side of the joint whereby pressure may be applied at the joint following the application of glue to the joint ends of said frame members. A wedge frame member may be included between the first mentioned frame members and the two joints thus formed may likewise be pressure bonded.

**APPARATUS FOR PRESSURE BONDING TWO OR MORE
FRAME MEMBERS IN THE FORMING OF FRAME
CORNERS**

The present invention relates to an apparatus for the press connecting of two or more wooden work pieces provided at their abutting sides with wedge-shaped tenons to form frame corners.

It is already known to make frame corners from bent oblong wooden pieces. For this on the one hand only woods of comparatively small cross section could be used and on the other hand it was not possible to bend such wooden pieces to form angular frame corners. It is also already known to cut through obliquely rectangular boards and to connect the two wooden workpieces thus resulting by gluing to form angular frame corners.

According to this method several wooden workpieces could be connected to one another to form a multiangular frame corner.

With this method the two abutting sides of the wooden workpieces forming between themselves the gluing joint were provided with glue and then pressed against one another. These frame corners could however not be subjected to any great stresses in the plane of the glued joint as only the holding force of the glue was decisive for the tensile strength and the abutting faces glued to one another were comparatively small. For increasing the tensile strength one then went over to providing the abutting faces with wedge-shaped tenons then depositing on these, glue and then pressing the tenoned abutting faces against one another.

In the latter method there then arose difficulties when constructional parts of large cross section had to be assembled to form supporting constructional parts. With large cross sections pressures of about 60,000 kg. are necessary in order to obtain a somewhat satisfactory connection. To apply such a force in a controlled manner failed with the conventional devices due to the fact that they were not transportable and necessitated such a space requirement which was frequently not available at the building site. It has already been proposed to insert on both sides of the glued joints, holes in the wooden workpieces, then to insert rods into these holes and then by means of a set of pulleys draw the rods together. On the one hand this method was complicated, time consuming and very expensive and on the other hand in doing so a uniform pressure could not be attained on all holes so that the holes were deformed to become partly oval. This known apparatus could not be realized economically.

The object of the present invention is to provide an apparatus of the above-mentioned kind which can easily be employed at building sites without large space requirements and produces a uniform high pressure corresponding to the requirements.

The apparatus according to the invention proposed for the solution of this problem is characterized by two pairs of bolts lying parallel and at the same distance from one another which engage through bores in which less stressed zones of the wooden workpieces to be connected to one another are provided and at their ends carry pressure transmitting members connected to one another in pairs contacting from top to bottom on the wooden workpieces with cross pieces connecting the pressure transmitting members on one wooden workpiece to one another, engage the piston rods of pressure medium cylinders which are mounted by means of crosspieces in holes of flat irons which are suspended on nose pieces of the pressure transmitting members lying on the other wooden workpiece. Thus it is of advantage for all parts of the apparatus lying above and below the wooden workpieces to be connected to be formed as mirror images. As pressure medium cylinders, hydraulic cylinders known per se as may be provided which are fed from a common pump.

It is also advantageous for the holes provided in the flat irons for the bearing of the crosspieces of the pressure medium cylinders to be formed as oblong holes in the longitudinal

extension of the flat irons. By means of these oblong holes the pressures medium cylinders may undergo a rough adjustment so that the piston stroke upon compression of the glued joint, is adequate.

5 The apparatus according to the invention is thus composed of several simple individual parts which according to their arrangement represent a positive connection whereby via the pressure medium cylinder an accurately adjustable uniform pressure can be produced. The number of devices used may be as desired corresponding to the width of the wooden workpieces to be connected to one another. As a rule however at least two devices are used in order to ensure an accurate pressure distribution. Instead of the pressure medium cylinders spindles may be employed which however is less advantageous.

10 A further construction according to the invention results due to the fact that the apparatus for the press connection of two wooden workpieces with the insertion of a further wooden workpiece with an additional bolt through which the inserted wooden workpiece engages which is supported against the outer sides of flat irons lying opposite the components exerting force during the pressing operation.

15 Furthermore for the more rapid bonding of the glue it is proposed according to the invention to arrange a steel band over the glued joint which is heated by resistance heating bands. Thus the glue joint is hardened in one to two minutes which ensures the full load-capacity of the constructional part after the complete hardening. The high frequency energy used hitherto for such purposes is not only uneconomic but cannot be used for reasons of the steel press parts present.

20 The cross pieces of the pressure medium cylinders may furthermore be supported according to the invention by means of slide shoes on the wooden workpieces which ensures a satisfactory guiding of the pressure medium cylinders opposite the wooden workpieces.

25 With the arrangement according to the invention bulky constructional parts may be composed of several wooden workpieces economically at the building site to form frame corners. The apparatus may of course also be employed where wooden workpieces have to be connected in a longitudinal expansion to one another on the building site.

30 The invention will be described in more detail with reference to the accompanying drawings which shows several optional embodiments:

35 FIG. 1 shows a curved frame corner;

40 FIG. 2 shows a frame corner composed of two wooden workpieces;

45 FIG. 3 shows a frame corner composed of three wooden workpieces;

50 FIG. 4 shows a view from above of two wooden workpieces to be connected to one another using three devices;

55 FIG. 5 shows a view like FIG. 4 wherein three wooden workpieces are connected to one another by means of two devices;

60 FIG. 6 shows on an enlarged scale compared with FIGS. 4 and 5 a device in side view;

65 FIG. 7 shows a view from above according to FIG. 6 with use of resistance heating bands;

70 FIG. 8 shows a press device including resistance heating bands. FIG. 1 shows a known frame corner made by bonding the wooden workpiece 1. The frame corner likewise known according to FIG. 2 consists of the two wooden workpieces 2 and 3 between the abutting faces of which a glue joint 5 is located. The frame corner according to FIG. 3 consists of the two outer wooden pieces 2 and 3 as well as an inserted wooden workpiece 4. Thus two glue joints 6 and 7 result.

75 The construction of the device according to the invention is explained in more detail with reference to the FIGS. 6 to 8 in which two wooden pieces 2 and 3 are connected to one another. The abutting faces of the wooden workpieces 2 and 3 are provided with wedge-shaped tenons 39 and 40 and from the glue joint 5. In the less stressed zones of the wooden workpieces 2 and 3 are disposed bores 12 which lie parallel to one

another and evenly spaced. For the making of the bores, templets known per se may be used. Through the bores 12, bolts 8, 9, 10 and 11 are inserted and on their ends 8a and 8b to 11a and 11b projecting on both sides from the bores 12 are fixed pressure transmitting members 13 to 20. On the pressure transmitting members 13, 14, 15 and 16 which contact the wooden work piece 2 are disposed nose pieces 30 to 33 on the flat irons 34 in which oblong holes are formed. In the opposite end of the flat irons 34 are provided further holes 29 formed as oblong holes in which engage nose pieces 42 of cross pieces 21 and 22 of pressure medium cylinders 25 and 26. The piston rods 23 and 24 of the pressure medium 25 and 26 press against the cross pieces 27 and 28 which connect the pressure transmitting members 17 and 19 and 18 and 20 to one another.

The pressure medium cylinders 25 and 26 are suitably supplied with pressure oil which is supplied via a common pump to provide a uniform pressure on all sides.

As can be seen in FIG. 8 in order to obtain a more rapid bonding of the glue, a steel band 36 with resistance heating bands 27 is placed around the glue joint 5 which resistance heating bands are connected to a transformer via pole clamps.

The crosspieces 21 and 22 of the pressure medium cylinders 25 and 26 may be formed on the side adjacent the wooden workpiece as a sliding shoe 38.

According to the embodiment in accordance with FIG. 4 two wooden workpieces 2 and 3 are provided with three devices according to the invention.

In the embodiment according to FIG. 5 the two wooden workpieces 2 and 3 are connected to one another with the insertion in between of a further wooden workpiece 4 using two devices. Thus there is provided in the central area of the wooden workpiece 4 a bore 43 into which a bolt 35 is inserted which is supported against the flat iron 34 when pressing together the three wooden workpieces 2, 4 and 3; the force components indicated by the arrows 44 and 45 cause a displacement of the wooden workpiece 4 upwards (in the plane of the drawing).

What I claim is:

1. An apparatus for the press connecting of two or more wooden workpieces provided on their abutting sides with wedge-shaped tenons to form frame corners, characterized by two pairs of bolts (8, 9, 18, 11) lying parallel and evenly

spaced apart which engage through bores (18) provided in the less stressed zones of the wooden workpieces (2, 3) to be connected to one another and at their ends (8a-11a and 8b-11b) carry pressure transmitting members (13-20) connected to one another in pairs contacting from top to bottom on the wooden workpieces (2, 3) and on crosspieces (21, 22) which connect together pressure transmitting members (17, 19) and (18, 20) on one wooden workpiece (3), and engage the piston rods (23, 24) of pressure medium cylinders (25, 26) which are mounted by means of crosspieces (27, 28) in holes (29) of flat irons (34) suspended on nosepieces (30-33) of the pressure transmitting members (13, 15 and 14, 16) in contact with the other wooden workpiece (2).

2. An apparatus according to claim 1, characterized in that all parts of the apparatus lying above and under the wooden workpieces to be connected are formed as mirror images.

3. An apparatus according to claim 1, characterized in that as pressure medium cylinders (25, 26) hydraulic cylinders known per se are provided which are supplied from a common pump.

4. An apparatus according to claim 1, characterized in that the holes (29) provided in that flat irons (34) for the bearing to the cross pieces (27, 28) of the pressure medium cylinders (25, 26) are formed as oblong holes lying in the longitudinal extension of the flat irons.

5. An apparatus according to claim 1, characterized in that the apparatus for the press connecting of two wooden workpieces (2, 3) with the insertion of a further wooden workpiece (4) with an additional bolt (35) engages through a bore (43) of the wooden workpiece (4) inserted there between whereby the bolt (35) is supported against the outside of these flat irons (34) which lie on the side of the apparatus lying opposite the force components (arrows 44, 45) occurring with the pressing operation.

6. An apparatus according to claim 1, characterized in that over the glue joint (5) a steel band (36) is disposed which is heated by resistance heating bands (37).

7. An apparatus according to claim 1, characterized in that the crosspieces (23, 24) of the pressure medium cylinders (25, 26) are supported on the wooden workpieces (2, 3) by means of sliding shoes (38).
